UNITED STATES PATENT OFFICE.

LAWRENCE CLYDE MOORE, OF PIQUA, OHIO, ASSIGNOR OF ONE-HALF TO JOHN HENRY MOORE, OF LIMA, OHIO.

DILUTING DEVICE FOR INTERNAL-COMBUSTION ENGINES.

Application filed February 2, 1922. Serial No. 533,550.

To all whom it may concern:

Be it known that I, LAWRENCE C. MOORE, citizen of the United States, residing at Piqua, in the county of Miami and State of Ohio, have invented certain new and useful Improvements in Diluting Devices for Internal-Combustion Engines, of which the following is a specification.

This invention relates to an improved diluting device for internal combustion engines and seeks, as one of its principal objects, to provide a device for introducing a mixture of heated air and steam into the fuel mixture of an engine for thus increasing the combustibility of the fuel mixture and accordingly increasing the efficiency of the engine while tending to cool the engine cylinders as well as deter the formation of carbon in the firing chambers of the cylinders.

A further object of the invention is to provide a device embodying a superheater for heating the air and steam and wherein the flow of mixed air and steam to the fuel mixture of the engine may be readily controlled.

And the invention has as a still further object to provide a device well adapted for use in connection with the various makes of engines as now upon the market.

Other and incidental objects will appear hereinafter.

In the drawings:

Figure 1 is a perspective view showing my improved diluting device in connection with a conventional internal combustion engine and radiator,

Figure 2 is a perspective view particularly showing the superheater and associated parts,

Figure 3 is a fragmentary section showing the manner in which the device is connected with the radiator,

Figure 4 is a fragmentary section of the superheater,

Figure 5 is a detail elevation of the distributor employed, parts being broken away and shown in section,

Figure 6 is a detail section showing a slightly modified construction,

Figure 7 is a plan view showing a modified form of control mechanism for the valve of the device, and

Figure 8 is a detail perspective view of the control mechanism illustrated in Figure 7.

Referring now more particularly to the drawings, I have shown my improved device in connection with a conventional internal combustion engine 10, the device being particularly adapted for use in connection with Ford engines. However, I do not wish to be limited in this regard since the device will prove equally efficient when used in connection with engines of other makes. The overflow pipe of the radiator is indicated at 12 and, as is well known, this pipe extends from a point within the filler tube of the radiator downwardly to a point exterior to the radiator. The intake manifold of the engine is indicated at 13 and the exhaust manifold at 14. Associated with the intake manifold is the engine carburetor 15.

In carrying the invention into effect, I employ a superheater comprising spaced parallel pipes 16 detachably connected near the rear ends thereof, as shown in detail in Figure 4, by a cross pipe 17 and closing the superheater pipes at their adjacent ends are plugs 18 threaded into the pipes so that the superheater pipes may be readily cleaned. As shown in Figure 1, the superheater pipes are arranged to straddle the exhaust manifold 14 of the engine extending longitudinally of the manifold, the pipes resting against the manifold to be effectually heated thereby, and leading forwardly from one of said pipes is a combined air and steam pipe 19. As shown in detail in Figure 3, the pipe 19 extends through the back wall of the top tank of the radiator 11 and is thence directed upwardly within the filler tube of the radiator to a point above the upper end of the overflow pipe 12 so that water in the radiator cannot rise to a level above the upper end of the pipe 19. Fixed upon said pipe at the back wall of the top tank is a sleeve 20 soldered or otherwise secured to the pipe and provided at its inner end with a stop shoulder 21. Interposed between this

100

shoulder and the inner face of the back wall is a gasket 22 while a similar gasket 23 is arranged upon the sleeve to confront the outer face of the back wall. Threaded upon the sleeve is a nut 24 which may be adjusted for tightly clamping the gaskets between said nut and the shoulder 21 coacting with the back wall of the top tank to provide a sealed joint. Thus, the pipe 19 may be readily connected with the top tank without the use of solder but to facilitate the mounting of the pipe upon the tank, I preferably form said pipe in sections and connecting said sections is an appropriate coupling 25. 5

15 Leading downwardly and rearwardly from the forward end of the other of the superheater pipes 16 is an outlet pipe 26 and interposed in said pipe is an appropriate control valve 27 operable by a lever 28. 20 Swingly connected at one end to this lever is a control rod 29 which extends rearwardly to a point where the rod may be conveniently reached so that the valve may be manually controlled with ease. At its rear 25 end the pipe 26 is connected to a distributor block 30. As shown in detail in Figure 2, the block 30 is shaped to fit between the confronting flanges of the manifold 13 and carbureter 15 and is secured by appropriate bolts extending between the flanges through the block. This block is formed centrally with a passage 31 registering with the passages of the carbureter and manifold and entering through one side of the block is 30 an opening 32 while at its opposite side the block is provided with a socket 33. Fitting through the opening 32 is a discharge nozzle 34 extending diametrically of the passage 31. At one end this nozzle snugly seats in the socket 33 while at its opposite end said nozzle is provided with threads to engage the threads of the opening 32 so that the nozzle is thus removably secured upon the block, and formed in the nozzle at its forward side is a plurality of discharge openings 35 leading into the passage 31. Threaded upon the lower end of the nozzle is an elbow 36 connecting the pipe 26 with the nozzle. 35

40 As will now be readily understood in view of the preceding description, when the engine is running and the valve 27 is open, engine suction will draw a mixture of steam and air from the radiator 11 through the pipe 19 into the superheater, air being supplied to the radiator through the overflow pipe 12. The mixture of steam and air will then flow rearwardly through one pipe of the superheater and then forwardly through the other pipe thereof so that the steam and air will be superheated, when the mixture will be thence drawn through the pipe 26 and into the nozzle 34 to be discharged into the intake manifold. Upon entering the 45

50

55

60

manifold, the mixture of steam and air will, of course, mingle with the fuel mixture in the manifold so that the fuel mixture will contain not only an auxiliary supply of oxygen but also a supply of moisture. As is well known, the combustibility of the fuel mixture will thus be appreciably enhanced for accordingly enhancing the efficiency of the engine while the presence of the moisture in the fuel mixture will tend to cool the engine cylinders. Furthermore, the moisture will, as is also well known, tend to prevent the formation of carbon in the cylinders. The valve 27 may, of course, be adjusted from time to time to regulate the flow of air and steam through the manifold in order to secure the best results. I accordingly provide an exceedingly efficient device for the purpose set forth and, as will now be appreciated, a device which may be readily installed. 65 70 75 80 85

In Figure 6 of the drawings, I have illustrated a slight modification which pertains more particularly to the superheater. In this figure, an engine block is indicated at 37 and the exhaust manifold of the engine 38. Integrally formed on the manifold at its upper side are superheater tubes or pipes 39 corresponding to the pipes 16 of the preferred construction. Accordingly, in this modification, the superheater is a permanent part of the exhaust manifold. 90 95

In Figures 7 and 8 of the drawings, I have illustrated a slightly modified form of control for the valve of the device, the device being shown, in Figure 7, in connection with the engine 40 of a Ford vehicle. The steering rod of the vehicle is indicated at 41, the throttle control rod at 42, and the spark control rod at 43. The superheater of the present device is indicated at 44, the outlet pipe leading from said superheater at 45, the control valve interposed in said pipe at 46, and the valve lever at 47. 100 105

In the present modification, I employ an arm 48 which, as shown, is fixed to the throttle control rod 42 and extending between said arm and the control valve lever 47 is a rod 49. Thus, when the rod 42 is rotated for opening the throttle valve of the engine, the valve lever 47 will be swung for coincidently opening the valve 46. Accordingly, the flow of hot air and steam to the intake manifold of the engine will be automatically regulated to conform to any increase or decrease in the flow of fuel mixture to the engine. 110 115 120

Having thus described the invention, what is claimed as new is:

In a diluting device for internal combustion engines, a rigid superheater unit including spaced superheater pipes to extend along the exhaust manifold of the engine resting on said manifold to be supported 125

throughout their length thereby, a cross pipe connecting the superheater pipes near corresponding ends thereof, removable plugs closing the superheater pipes at said ends thereof, a combined air and moisture supply pipe for connecting the opposite end of one of said superheater pipes with a radiator a distributer for interposition be-

tween the engine carbureter and intake manifold forming a connection between the ¹⁰ outlet of the carbureter and the intake of the manifold, and an outlet pipe connecting the opposite end of the other of said superheater pipes with said distributer.

In testimony whereof I affix my signature.
LAWRENCE CLYDE MOORE. [L.S.]
